(57) **CLAIM**

The ornamental design for a cross-shaped display stand, as shown and described.

DESCRIPTION

FIG. 1 is a top front perspective view of a cross-shaped display stand in accordance with the present invention;

FIG. 2 is a bottom rear perspective view thereof;
FIG. 3 is a front view thereof;
FIG. 4 is a rear view thereof;
FIG. 5 is a right side view thereof, with the left side view being a mirror image;
FIG. 6 is a top view thereof;
FIG. 7 is a bottom view thereof;
FIG. 8 is a top front perspective view of another embodiment of a cross-shaped display stand in accordance with the present invention;
FIG. 9 is a bottom rear perspective view thereof;
FIG. 10 is a front view thereof;
FIG. 11 is a rear view thereof;
FIG. 12 is a right side view thereof, with the left side view being a mirror image;
FIG. 13 is a top view thereof;
FIG. 14 is a bottom view thereof;
FIG. 15 is a top front perspective view of another embodiment of a cross-shaped display stand in accordance with the present invention;
FIG. 16 is a bottom rear perspective view thereof;
FIG. 17 is a front view thereof;

FIG. 18 is a rear view thereof;
FIG. 19 is a right side view thereof, with the left side view being a mirror image;
FIG. 20 is a top view thereof;
FIG. 21 is a bottom view thereof;
FIG. 22 is a top front perspective view of another embodiment of a cross-shaped display stand in accordance with the present invention;
FIG. 23 is a bottom rear perspective view thereof;
FIG. 24 is a front view thereof;
FIG. 25 is a rear view thereof;
FIG. 26 is a right side view thereof, with the left side view being a mirror image;
FIG. 27 is a top view thereof; and,
FIG. 28 is a bottom view thereof.
The evenly dashed broken lines are shown for the purpose of illustrating environmental subject matter that form no part of the claimed design. The dot-dash broken lines are shown for the purpose of illustrating the boundaries of the claim and form no part thereof.
